UNITED STATES PATENT OFFICE

GEORGE F. WEATON, OF BEAVER, PENNSYLVANIA, ASSIGNOR TO ST. JOSEPH LEAD COMPANY, OF NEW YORK, N. Y., A CORPORATION OF NEW YORK

METALLURGICAL CONDENSER

Application filed February 26, 1933. Serial No. 595,365.

This invention relates to a metallurgical condenser, and is particularly adapted to the condensation of zinc vapors arising from the reduction of zinciferous materials in shaft or rectangular vertical retort furnaces of the electrothermally or externally heated types or in furnaces combining electrothermal and external heating.

One of the most serious problems in the smelting of zinc is the efficient condensation of the zinc vapor without the production of large amounts of troublesome blue powder. The empirically worked out condenser designs which have given a degree of satisfactory performance in the smelting of zinc in the conventional horizontal retorts have proved to be entirely inapplicable to the radically different conditions presented by the smelting of zinc in electrothermally or externally heated shaft or vertical retort furnaces. Chief among these different conditions are the increased volume of vapor to be handled and the altered ratio of zinc vapor to non-condensable gases produced in such furnaces.

The increased volume of gases cannot be effectively compensated for by merely proportionately increasing the size of previously used condensers for the reason that such an increase in size results in different ratios of volume to effective condensing surface and effective radiation surface of the condenser. Relative gas velocities and rates of diffusion also play important roles in the condensation problem and their effect on the efficiency of condensation must be taken into account in condenser design.

The ratio of zinc vapor to non-condensable gases directly effects vitally important condensation conditions. The initial temperature of condensation decreases with increasing dilution of the zinc vapor by non-condensable gases, while the residual uncondensable zinc content of the gases at any given temperature will, of course, increase with increasing dilution of the zinc vapor.

Provision must be further made in an efficient condenser for the coalescence of minute drops of condensed liquid zinc and it is particularly desirable to provide for the positive assistance of such coalescence.

The condenser of the present invention is particularly adapted for the effective condensation of zinc vapor coming from electrothermally and externally heated shaft or vertical retort furnaces. It provides the proper ratios of condensation surface, radiation surface, gas volume and gas velocities. It provides the proper temperature gradient for efficient condensation of zinc vapor from the progressively impoverished gases passing through the furnace. It provides positive assistance to the coalescence of the small drops of liquid zinc collecting on the condensation surfaces. It provides further a simple and effective construction, readily accessible for inspection, cleaning and repair, and of the utmost simplicity and efficiency of control.

The invention will be more fully described with reference to the embodiment illustrated in the accompanying drawing, in which:

Figure 1 is a vertical section on line 1—1 of Figure 2;

Figure 2 is a partial horizontal section on line 2—2 of Figure 1; and

Figure 3 is a vertical section on line 3—3 of Figure 1.

Vapors from the smelting zone 1 are admitted into annular chamber 2, if a shaft type furnace; or, if a rectangular furnace, this chamber may be parallel to the length of the furnace at any desired elevation, connection being made into the annular chamber 2 by a plurality of ports 3. Advantageously the effective area of the ports is sufficient to maintain a velocity of 60 to 70 feet per minute through said ports, the vapors debouching into chamber 2 where condensation will begin.

To complete the condensation, main condenser 4 is attached at suitable intervals to chamber 2. Condensing chamber 4 is preferably made narrow and high, the preferred ratio of width to height being 1:5. Length will be adjusted to suit the particular installation on the basis of the amount of vapor it is desired to condense, it having been found in practice that a condenser such as here described, including chamber 2, should preferably provide from $2\frac{1}{4}$ to $2\frac{3}{4}$ square inches

of condensing surface, including baffles, per pound of vapor per 24 hours.

The condenser 4 is provided with a plurality of inclined baffles 5 and 5a extending from side to side of the condenser. As will be clearly seen from the drawing, baffles 5 are spaced from the top at their upper end and extend downward to a point near the bottom of the condenser chamber, where they 5

10 cooperate with the pool of liquid metal retained in the bottom of the chamber to prevent the flow of gases under these baffles. Alternate baffles 5a contact with the top of the chamber at their upper ends and extend 15 downward to a point above the surface of the pool of liquid metal in the condenser chamber.

Passing out of chamber 2 into main condenser 4, the vapors are caused to impinge 20 against the first of the baffles 5, which will change their direction, causing the major portion of the gases or vapors to travel over the top of said baffle 5, passing downward between 5 and 5a, then again upward, taking a sinuous path between baffles 5 and 5a until the uncondensed gases finally pass out from exit 6. The baffles 5 and 5a are inclined, preferably at an angle of about 22½° with the vertical. Due to the regularity of 25 the vapor production by the furnace of the type for which the condenser is especially adapted, insulation 7 on condenser 4 may be advantageously installed in a permanent manner. Baffles 5 and 5a and lining 8 of 30 the condenser may be made of silicon carbide or cast mullite, these refractories not being readily attacked by zinc at the temperatures prevailing within the condenser. Temperatures within the condenser are indicated by pyrometers 9. Regulation of the 35 furnace pressure may be effected by regulation of the size of the orifice in exit 6. Metal is withdrawn from the condenser through tap block and spout 10. Access holes 11 are 40 provided by means of which any accretions which form within the condenser may be loosened and raked out. The whole condenser may be set in a steel box 12 filled with finely crushed coke 13 well covered with fire 45 clay, upon which is placed a base of firebrick 14.

A particularly valuable characteristic of the inclined baffles of the condenser of the invention is the positive assistance which 55 they provide to the coalescence of small particles of liquid zinc formed in the condensation. The minute particles of zinc formed by condensation from the vapor will be deposited principally upon the upper surfaces 60 of baffles 5 and 5a, although some deposition will take place on the lower surfaces of these baffles also. The velocity of the gases and vapors and such condensed metal as has already coalesced is sufficient to disturb any 65 small, uncoalesced globules and to start them

rolling and sliding down the inclined surfaces of baffles 5 and 5a, promoting their coalescence with larger globules and with the main body of metal. This action is very efficient in practice and permits the complete and effective condensation of the large volumes of vapors furnished by reduction furnaces of great capacity. 70

I claim:

1. A metallurgical condenser comprising a 75 chamber, a plurality of inclined baffles spaced from the top of said chamber and extending below the normal level of liquid metal in said chamber, and a plurality of inclined baffles alternating with said first-named baffles and 80 extending from the top of said chamber to a level above the normal level of liquid metal in said chamber.

2. A metallurgical condenser comprising a 85 chamber and a plurality of baffles inclined at an angle of about 22½° with the vertical providing a tortuous up-and-down path for the gases therethrough.

3. A metallurgical condenser comprising a 90 chamber, a plurality of baffles, inclined at an angle of about 22½° with the vertical, spaced from the top of said chamber and extending below the normal level of liquid metal in said chamber, and a plurality of baffles alternating with said first-named baffles and similarly inclined, extending from the top of said chamber to a level above the normal level of liquid metal in said chamber. 95

4. A metallurgical condenser comprising a 100 rectangular chamber having a ratio of width to height of about 1 to 5, a plurality of baffles, inclined at an angle of about 22½° with the vertical, spaced from the top of said chamber and extending below the normal level of liquid metal in said chamber, and a plurality of baffles alternating with said first-named baffles and similarly inclined, extending from the top of said chamber to a level above the normal level of liquid metal in said chamber. 105

5. A method of condensing metallic zinc from gases containing zinc vapor which comprises passing said gases in a relatively narrow stream in a tortuous up-and-down path in contact with inclined condensing surfaces, the zinc vapor being passed at a rate of about one pound per 24 hours per 2½ square inches of condensing surface. 110

In testimony whereof, I affix my signature.

GEORGE F. WEATON.
